INTERNAL COMBUSTION ENGINE

Herbert C. Edwards, Detroit, Mich., assignor to
Packard Motor Car Company, Detroit, Mich.,
a corporation of Michigan

Application May 14, 1934, Serial No. 725,477

13 Claims. (Cl. 123—145)

This invention relates to internal combustion engines and more particularly to glow plugs.

In order to assist in starting compression-ignition engines using air and fuel oil as the fuel charge, it has been found advantageous to employ some form of heating means to assist combustion. It is conventional practice to provide the combustion chambers of such engines with glow plugs which consist of a body, an electrode insulated from the body and connected with a source of electric supply, and a bare resistance wire secured at its ends to the body and electrode.

Considerable difficulty has been encountered in developing glow plugs capable of withstanding the heat, vibration and forces to which they are subjected in the combustion chambers of compression-ignition engines, and particularly when such engines are designed to operate at high speeds. The main difficulty has been found to reside in wire failure due to fatigue at the end connections and burning out intermediate the ends because of shorting contact with the electrode. Relatively large diameter wire has sufficient body so that it is generally self sustaining to an extent such that the vibration and the force of turbulence, compression and explosion in the combustion chamber will not move it into shorting contact with the electrode. Some wire has characteristics or is of such small diameter that it is not self sustaining and, under such circumstances, it must be supported intermediate its ends in an insulated relation with the electrode. It has been proposed to apply formed sleeves of insulating material on the electrode and to provide wire receiving recess means on the periphery of the sleeves, but it has been my experience that such sleeves expand and contract differently than the electrode and this, together with the vibration, heat and forces in the combustion chambers combine in soon cracking the sleeves so that they disintegrate. Such disintegration allows the wire to contact with the electrode and the sleeve chips to score the pistons and cylinders and otherwise cause disastrous results to other engine parts.

An object of my invention is to provide glow plugs which will withstand long usage in high speed engines of the compression-ignition type.

Another object of the invention is to provide a glow plug having high resistance wire associated with an electrode in a manner such that it will function properly for a long period of use in a high speed compression-ignition engine.

A further object of the invention is to provide a new and novel form of electrode for glow plugs.

Still another object of the invention is to provide a glow plug in which the electrode, on which a resistance wire is wound, is coated with a heat resisting material having qualities such that the contraction and expansion will be similar to that of the electrode.

Other objects of the invention will appear from the following description taken in connection with the drawing, which forms a part of this specification, and in which:

Fig. 1 is a side elevational view of a glow plug which incorporates my invention enlarged several times its normal size;

Fig. 2 is a longitudinal sectional view of the same.

Referring now to the drawing by characters of reference, 10 indicates the glow plug body which is provided with a knurled flange 11 at one end and a threaded periphery 12 at the other end. The threaded portion of the body is adapted to be screwed into an opening in the cylinder structure of a compression-ignition engine until the flange 13 bears against a cylinder surface. Through the glow plug body extends an axially disposed circular bore 14 which gradually increases in diameter from the knurled end toward the threaded end.

Extending through the bore 14 in the body is an electrode 15 having one end 16 projecting past the knurled body flange and threaded peripherally 30 and the other end projecting past the body end 12 and threaded as indicated at 17. The portion of the electrode within the body is similar in cross section to the body bore but is of slightly less diameter so that an insulator sleeve 18, preferably formed of mica, can be interposed therebetween. A ring abutment member 19, formed of insulation material such as mica, surrounds the threaded end 16 of the electrode and engages an end of the body, such element serving to locate the mica sleeve. Surrounding the threaded end 16 of the electrode and engaging the abutment member is a washer 20 and a nut 21 is screwed on this end of the electrode and serves to secure the previously described elements in a definite relation. It will be seen that, as the nut is turned on the shaft toward the body, it will wedge the body and the electrode together. An electric cable 22 leads from a source of electric supply and is provided at its end with a contact clip 23 which is telescopically on the threaded end 16 of the electrode. The clip is held against the nut 21 by a nut 24 which is screwed on the electrode.

The glow plug resistance wire is indicated at 25, one end 26 of the wire being projected into an

opening 40 in the threaded end of the glow plug body and suitably retained therewith by peening a portion of the body as indicated at 27. The other end 28 of the resistance wire is secured to the end of the electrode projecting past the threaded end of the body. In the present instance, a groove 29 is formed to extend substantially radially in the end of the electrode and terminates in a recess as indicated at 30. The wire end 28 projects into the recess 30 and is bent to lie in the groove 29. The intermediate portion of the resistance wire is coiled around the electrode as will be hereinafter described.

The resistance wire illustrated in the drawing 15 is of such small cross section that it is incapable of sustaining itself against the vibration, heat and forces developed within the combustion chamber, into which it projects, without quickly becoming fatigued to an extent soon resulting in breakage 20 or burning. I have found therefore, that, with a heating wire of this type, it is necessary to provide a support for it and in the present invention I have utilized the central electrode for this purpose. In so supporting the heating wire I 25 have provided a heat resisting insulation material between the wire and the electrode.

It is the purpose of this invention to provide a heat resisting insulation material between the electrode and the coil of the resistance wire which 30 will be of a character such that it will expand and contract with the electrode and, at the same time, serve as a mandrel on which the wire can be tightly wound in order to serve as both a support for the wire and means for retaining it in a pre- 35 determined coiled relation.

As above set forth, the electrode is formed with a peripheral recess in the form of a thread 17 which extends helically. I propose to coat the threaded portion of the electrode with an insulation material having a high heat resistance and characteristics such that it will expand and contract in substantially the same manner as the electrode. To this end, I propose to employ a 40 vitreous material in the form of porcelain enamel 45 which is applied so that it forms a thin coating on the threaded portion of electrode as indicated at 31 in the drawing.

The porcelain enamel can be formed of materials in the following proportion: 400 pounds 50 of frit, 20 pounds of clay, and 12 pounds of black oxide. To this mixture is added 140 pounds of water and the entire mass is then mixed in a porcelain lined mill until it is of fine mesh. Such mixture is then preferably allowed to stand for a 55 week during which time there is a chemical reaction between the clay and the frit. The excess water rises to the top of the mixture, after it stands, leaving a relatively thick substance therebelow and such excess water is removed and the 60 remaining substance is placed in a tank or a spray for the purpose of either dipping or spraying the threaded portion of the electrode so that a coating of material will be placed thereon. The electrode so coated is then dried at a temperature 65 of about 200° Fahrenheit and then put in an oven and fused, at a temperature of about 1420° Fahrenheit, for a period of ten to twenty-five minutes. I have found that the clay provides a plastic quality so that the layer of porcelain on 70 the electrode will readily expand and contract in the same proportion as the electrode without cracking.

The wire is wound tightly against the porcelain in the thread recess of the electrode and the ends 75 are secured as previously described. I have found

that glow plugs of such character will withstand many hours of operation without the porcelain cracking and without the wire becoming fatigued.

Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. A glow plug for internal combustion engines comprising a body, an electrode insulated from and carried by the body, a thin coating of porcelain on one end of the electrode, and a resistance wire secured at its ends to the body and the electrode respectively, an intermediate portion of the wire being coiled against the porcelain coating on the electrode.

2. A glow plug for internal combustion engines comprising a body, an electrode insulated from and carried by the body, an end of the electrode projecting beyond an end of the body being peripherally recessed, a coating of porcelain on the recessed projecting end of the electrode, and a resistance wire wound tightly against the porcelain coating in the recessed portion of the body and secured at its ends to the body and the electrode respectively.

3. An electrode for glow plugs comprising a body formed of metal, peripheral threads on one end of the body, and a porcelain coating on the threaded surface of the body.

4. An electrode for glow plugs comprising an elongated metal body having threads formed around a portion thereof.

5. An electrode for glow plugs comprising a metal body having the periphery of one end formed with a helical recess, and a porcelain coating baked on the recessed end of the body.

6. A glow plug for internal combustion engines comprising a body, an electrode insulated from and carried by the body, said electrode having a peripheral helical recess in a portion thereof, a thin porcelain coating over the recessed portion of the electrode, and a resistance wire wound in the recess in engagement with the porcelain, one end of the wire being attached to the electrode and the other end of the wire being attached to the body.

7. An electrode for glow plugs comprising a metal body having a peripheral wire receiving groove in a portion thereof, and a porcelain enamel coating formed on the grooved portion of said body.

8. An electrode for glow plugs comprising a metal body having a spiral thread on the periphery of an end portion thereof, and an insulation coating applied to the threaded portion of said body.

9. An electrode for glow plugs comprising a body having a peripheral recess around a portion thereof, and insulation means applied to and baked on the body to cover the recess surfaces.

10. An electrode for glow plugs comprising a body having wire retaining means formed therein, and an insulation coating baked on the portion of body having the wire retaining means therein, said coating being formed of material having a plastic quality when subjected to heat.

11. In a glow plug, inner and outer metallic members having small openings of uniform diameter extending upwardly from their lower ends, one of said members projecting beyond the other and carrying in its projecting portion a helical

groove extending from adjacent the opening in the lower end of one member to adjacent the opening in the lower end of the other member, a glow wire having its opposite end portions extending upwardly and completely enclosed by and filling said openings, and its exposed intermediate portion seated in said groove, and an adherent coating of non-conducting material on said grooved projection.

5 10 12. An electrode for glow plugs comprising a

metal body having a portion of the periphery formed with a wire receiving recess, and a coating formed on the recessed portion of said body, said coating having heat resisting and insulating characteristics.

13. An electrode for glow plugs comprising a 5 metallic body having a peripherally grooved portion, and an adherent coating of non-conducting material on the grooved portion of said body.
